UNITED STATES PATENT OFFICE.

RALPH C. SIMMONS, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR OPERATING UPON HEELS.

1,143,921.

Specification of Letters Patent. Patented June 22, 1915.

Original application filed April 23, 1909, Serial No. 491,785. Divided and this application filed June 10, 1910. Serial No. 566,202.

To all whom it may concern:

Be it known that I, RALPH C. SIMMONS, a citizen of the United States, residing at Beverly, in the county of Essex and State of Massachusetts, have invented certain Improvements in Machines for Operating Upon Heels, of which the following description, in connection with the accompanying drawings, is a specification, like reference 5 characters on the drawings indicating like parts in the several figures.

This invention relates to machines for operating upon boots and shoes and more particularly to machines for operating upon 15 heels, such for example as is described in my copending application for United States Letters Patent, Ser. No. 491,785, filed April 23, 1909, of which the present application is a division.

20 In breasting heels it is sometimes desirable for ornamental effect to breast heels by cuts which are oblique to the longitudinal median lines of the heels. It is generally customary to have the breasts of the heels 25 incline forwardly toward the outer side of the shoe so that a right heel will be breast by a cut which is oppositely inclined to that of a left heel.

An object of the present invention is to 30 provide an improved machine for breasting heels which is adapted to breast right and left heels by cuts having the proper angular relation to the longitudinal median lines of the heels.

35 A further object of the invention is to provide improved positioning means for locating the shoe with its heel in proper operative relation to the breasting knife.

With these and other objects in view the 40 present invention contemplates the provision in a heel breasting machine in which the shoe is movable to position the heel of the shoe in proper angular relation to the breasting knife of means for positioning a shoe 45 so that its heel will be breast by a cut having the desired inclination to its longitudinal median line. The construction is preferably such that right and left heels may be accurately positioned in such relation to 50 the knife that they will be breast respectively by cuts having equal and opposite inclinations. Preferably also the means for determining the right and left alinements

of the shoe comprise gages arranged to have direct engagement with opposite sides of the 55 shoe as with this construction a shoe may be more accurately positioned with relation to the breasting knife than would otherwise be the case.

While in its broader aspects the present 60 invention contemplates the provision of gages which are arranged to engage opposite sides of any suitable part of the shoe the arrangement is however preferably such that the gages are adapted to have contact 65 with opposite sides of the heel, as owing to the symmetrical shape of the heel the right and left alinements may be determined more accurately with this arrangement than would be the case if the gages had engagement with an unsymmetrical part of the 70 shoe such for example as the forepart of the sole.

In the embodiment of the invention hereinafter described the breast end of a heel 75 sustained within the positioning device is free to have a limited movement transversely of its longitudinal median line, the shoe sustaining means being constructed to permit tilting movement of the shoe relatively to 80 said means, and the rounded end of the heel is restrained from transverse movement so that the shoe may be tilted about an axis which extends longitudinally of the knife in proximity to said rounded end to position 85 the heel in the desired angular relation with the breasting knife. The means for limiting the tilting movement of the shoe comprise gages arranged for engagement with the opposite sides of the heel and to be adjusted 90 equally and in opposite directions.

The side gages or rests, as shown, are of short vertical length so as to engage the top portion only of the sides of the heel. This top portion may comprise a top lift which 95 usually has the final shape of the heel whether or not the heel has already been trimmed.

The means for restraining the rounded end of the heel from transverse movement 100 may comprise a member having inclined faces for engaging the sides of the heel, preferably in a plane substantially below the top lift of the heel of the inverted shoe, whereby the member co-operates with the 105 other gages to prevent rocking movement of

the shoe heel under the action of the knife. This member which restrains the heel from transverse movement is preferably held resiliently in forward position and is moved 5 rearwardly by pressure of the shoe heel against its inclined faces, thereby acting to center the shoe transversely relatively to the knife. To coöperate with this centering member which centers the heel and prevents 10 transverse movement thereof an adjustable rigid back gage or stop is provided which contacts with the rear edge face of the top lift and limits the rearward movement of the heel relatively to the knife, whereby the 15 length of the shoe heel is adjustably determined.

In the embodiment of the invention above referred to the operator tilts a right shoe in one direction and a left shoe in the opposite 20 direction in order to position the shoes in proper relation to the knife, the extent of the tilting movements of the shoes being respectively limited by the gages. As the gages are continuously sustained in position 25 to be engaged by the sides of a shoe it will be seen that in changing from a right shoe to a left shoe, or vice versa, no adjustment of the positioning device is required as it is only necessary for the operator to tilt a 30 right shoe in a direction opposite to that of a left until its tilting movement is limited by the gage corresponding to the shoe being operated upon.

These and other features of the invention 35 will appear more fully from the following description when read in connection with the accompanying drawings, and will be pointed out in the appended claims.

In the drawings,—Figure 1 is a view in 40 side elevation of a heel breasting machine provided with a shoe positioning device embodying the present invention; Fig. 2 is a plan view of the positioning device shown in Fig. 1, looking upward toward the line 45 9—9 of said figure.

The frame 94 of the shoe positioning device shown in said figures is pivoted at 96 to the lower end of a slide 8. A projection 98 extending upwardly from the frame 94 is arranged to engage a bolt 14 of the holder and a spring 100 extending between the holder and frame serves to hold the projection 98 in engagement with the end of said bolt. The frame 94 carries a plate 102 which is adapted to engage the tread portion 50 of the heel of a shoe carried by the shoe support 6 to clamp said shoe in operative position. A shoe support 6 which sustains the shoe in the path of the knife fits loosely 55 in the shoe, whereby a tilting movement of the shoe relatively to the support is permitted so that the longitudinal median line of the heel may be positioned in an oblique relation to the knife. To limit movement 60 of the shoe into operative relation with the

breasting knife there is provided a gage 104 which is adapted to be engaged by the rounded end of the heel of the shoe, and is carried by a limiting plate 106 mounted for sliding movement, in guideways formed in 70 the frame 94, in a direction substantially parallel with the line of movement of the shoe into operative position. A worm 108 rotatably mounted between ears projecting from the frame 94, extends through an opening formed in the outer wall of one of the guideways and meshes with teeth 110 formed upon one of the edges of the plate 106. The worm 108 is constructed to be manipulated by the operator so that the limiting plate 106 may be conveniently moved 75 into different adjustments. A centering slide 112 having a V-shaped recess adapted to center the rounded end of a heel with relation to the gage 104 is mounted in the 80 guideways below the plate 106. A torsional spring 114 having one end secured in fixed relation to the frame 94 and its other end engaging a stud 116 secured in the slide 112 serves to yieldingly press the latter toward the 85 heel. A pin 118 formed to be inserted in any one of a series of openings 120 in the centering slide 112 is adapted to engage the limiting plate 106 to limit forward movement of the slide. With the construction 90 above described the rounded end of the heel of the shoe may be accurately centered by the slide as said heel is moved toward the 95 gage 104 which limits its movements.

By manipulating the worm 108 the gage 100 100 104 may be adjusted so that the length of the heel as determined by the breasting operation will be in accord with the width of said heel.

In the present device the rounded end of 105 a heel in operative position is restrained from lateral movement by the V-shaped recess in the plate 112 so that the shoe may be readily tilted about an axis in proximity to said rounded end, to position the heel in the 110 desired angular relation to the breasting knife. To limit the extent of this movement there is provided means for limiting lateral movement of the breast end of the heel in 115 opposite directions respectively. According to a convenient construction two gages 122 are arranged upon opposite sides of the pressure plate 102 in positions to be engaged by the edges of the heel in proximity to its 120 breast corners. The gages 122 respectively depend from gage slides 124 arranged in a guideway formed in the plate 102 transversely of the line of movement of the heel into operative position. The slides 124 are 125 interconnected by a right and left hand threaded screw 126 having a milled head 128 adapted to be manipulated by the operator. The plate 112 is located below the plane of the rests or gages 122 a distance which, as 130 shown, is approximately half the height of

the average heel, and, therefore, coöperates with the rests not only to limit lateral turning movement of the heel but also to prevent rocking of the shoe under the action of the 5 knife. The operation of this device will be readily understood from the foregoing by those skilled in the art without further description thereof.

It will be seen that in accordance with the 10 present invention a shoe and an operating tool may be relatively positioned in accordance with the size of the shoe which is of assistance in insuring that the work turned out by machines provided with a positioning 15 device embodying the present invention will be accurately performed, and that the work will be of uniform quality.

Although it has been herein stated that the present device is adapted to relatively 20 position a shoe and an operating tool it will however be understood that the invention is not limited for use with boots and shoes in accordance with a strict definition of these terms.

25 Devices embodying the present invention may be employed not only to position shoes themselves but any part of a shoe as for example a heel or the rounded end of the upper and still fall within the scope of the invention. Moreover the present invention is 30 equally applicable to devices for positioning lasts or to devices for positioning any article having a shape similar to that of a shoe or to any part thereof.

35 It will be further understood that although the present device is employed to relatively position a shoe and an operating tool the invention is applicable to devices for relatively positioning a shoe and some 40 article other than an operating tool. For example where it is desired to relatively position any two parts of a shoe a device embodying the present invention could be readily employed to effect this result.

45 Having described my invention, what I claim as new and desire to secure by Letters Patent of the United States is:—

50 1. A shoe positioning device, having in combination, means for laterally centering the rounded end of a heel, and means arranged to contact with the heel and to permit a limited free lateral movement of the breast end of the heel in opposite directions respectively.

55 2. A shoe positioning device, having in combination, means for laterally centering the rounded end of a heel, and means for engaging opposite edges of the heel in proximity to its breast corners arranged to permit a limited free lateral movement of said breast end in opposite directions respectively.

60 3. A shoe positioning device, having in combination, means for limiting the movement of a heel in the direction of its length

arranged for engagement with the rounded end of the heel and constructed to center said end in the movement of the heel into operative position, and gages for engagement with opposite sides of the heel arranged to permit a limited tilting movement of the latter about an axis in proximity to the center of its rounded end. 70

4. In a shoe positioning device, means for centering a shoe heel, means normally pressing the centering means forward, adjustable means for limiting the forward movement of the centering means, and adjustable means for limiting the lateral movement of the breast end of the heel in both directions. 75

5. A heel breasting machine, having in combination, a breasting knife, a support for sustaining a shoe in the path of the knife constructed to permit tilting movement of the shoe to allow the latter to be positioned 85 with the longitudinal median line of its heel in an oblique relation to the knife, a member arranged for clamping engagement with the tread surface of the heel, and means carried by said member for limiting the said tilting 90 movement of the shoe.

6. A heel breasting machine, having in combination, a breasting knife, a support for sustaining a shoe in the path of the knife constructed to permit tilting movement of 95 the shoe to allow the latter to be positioned with the longitudinal median line of its heel in an oblique relation to the knife, and gages for limiting said tilting movement in opposite directions respectively arranged for engagement with opposite sides of the shoe, said gages being continuously sustained in working positions in which they may be selectively employed to position a shoe carried upon the said support. 100

7. A shoe positioning device, having in combination, a member having engagement with the rounded end of the heel, and means for limiting free lateral movement of the other end of the shoe comprising gages arranged to engage opposite sides of the heel. 105

8. A heel breasting machine, having in combination, a breasting knife, a support for sustaining a shoe in the path of the knife constructed to permit the shoe to be positioned with the longitudinal median line of 115 its heel in an oblique relation to the knife, and gages arranged for engagement with opposite sides of the heel carried by the support, said gages being continuously sustained in working position.

9. In a shoe positioning device, a frame, a limiting plate slidably mounted in said frame and provided with a rack on its edge, a worm carried by the frame and engaging the rack, a centering slide, a spring arranged to press said slide forwardly, a pin on said centering slide adapted to engage the limiting slide, a pressure plate, gage slides in the pressure plate, gages on the 120 125 130

- gage slides, and a right and left hand screw engaging the gage slides for adjusting the gages to and from each other.
10. A heel breasting machine having, in combination, a breasting knife, a support for sustaining a shoe with its attached heel in the path of the knife, and means for preventing rocking movement of the shoe under the action of the knife comprising a 10 plate engaging the tread surface of the heel, a rest of short vertical length engaging the upper portion only of the side of the heel near the breast, and a rest having inclined faces for engaging the sides of the heel at the rear and movable longitudinally of the heel.
11. In a heel breasting machine, a reciprocating knife, a support for sustaining a shoe in the path of the knife, a centering 20 device for the heel, a presser plate engaging the tread surface of the heel, and rests opposite the breast end of the top lift against either of which shoes may be pressed by the operator to position the same for 25 rights and lefts and to prevent tipping of the shoe under the action of the knife.
12. In a heel breasting machine, a knife, a support for opposing the shoe to the action of the knife, rests mounted for adjustment 30 to and from the longitudinal median line of the shoe for engaging the top portion only of the sides of the heel, and a resiliently held centering member having inclined faces for engaging the sides of the heel in a plane substantially below the tread face of the top lift, whereby the centering device coöperates with the rests to prevent 35 rocking of the shoe under the action of the knife.
40. 13. In a heel breasting machine a reciprocating knife, a support for holding the shoe against displacement in the direction of movement of the knife, rests arranged to engage the sides of the forepart of the heel, means for simultaneously adjusting said rests toward and from the longitudinal median line of the heel, a stop for limiting movement of the shoe longitudinally relatively to said knife and said rests, and 45 a centering device relatively to which the shoe is turned to engage said rests, said centering device being located in a plane substantially below the plane of the tread face of the top lift and coöperating with either

of said rests alternatively to hold the shoe 55 against rocking movement when the shoe is positioned with the heel into contact with either of said rests.

14. In a heel breasting machine, a knife, a plate for applying pressure to the tread 60 face of the heel, a resiliently held member having inclined faces for centering the heel, and a rigid stop for limiting movement of the heel into heel breasting position relatively to the knife, said stop being adjustable for varying the extent of said movement of the heel.

15. In a heel breasting machine, a reciprocating knife, a support for opposing a shoe to the action of the knife, a plate movable toward and from the shoe and arranged to engage the tread face of the heel, gages carried by the plate in position to contact alternatively with the top portions 70 of the sides of the heel, and a centering device for locating the rear portion of the heel laterally relatively to the gages, said device being located below the plane of the heel engaging surface of the plate and co-operating with either of said gages to limit 75 lateral turning movement of the shoe and to locate the heel for the action of the knife.

16. A shoe positioning device, having, in combination, means for preventing lateral movement of one end of a heel, and means 80 for limiting the lateral movement of the other end of the heel in opposite directions respectively, constructed and arranged for 85 engaging the edges of the heel adjacent to the breast upon opposite sides.

17. A shoe positioning device, having, in combination, a guideway, a slide in the guideway having a V-shaped recess for receiving the rounded end of a heel and arranged to yield to the movement of the 90 heel, a second slide in said guideway having a gage for limiting the movement of the heel, and means for adjusting said second slide in the direction of movement of the heel.

In testimony whereof I have signed my name to this specification in the presence of two subscribing witnesses.

RALPH C. SIMMONS.
